INTERCHANGEABLE SELF-CLEANING RAKE

Laudie J. Mruk, Milwaukee, Wis.

Application April 11, 1938, Serial No. 201,280

1 Claim. (Cl. 56—400.20)

My invention relates to improvements in interchangeable self-cleaning rakes of the type ordinarily used for raking lawns.

The object of my invention is to obtain increased efficiency at reduced cost of construction.

More specific objects are to so connect the handle with the back of the rake as to allow the handle to be used interchangeably for rakes of differing sizes, and utilize certain of the teeth to limit the swinging movement of the rake with reference to the handle, when the teeth are swung into and out of cleaning position.

In the drawing:

Figure 1 is a perspective view of my improved rake.

Figure 2 is a sectional view of the metal parts, drawn to line 2—2 of Figure 1, but showing the spring in full.

Figure 3 is a fragmentary sectional view of the cast metal back, showing paired embedded tooth forming rods.

Figure 4 is a fragmentary detail showing the handle clamping member as seen from the under side.

Like parts are identified by the same reference characters throughout the several views.

My improved rake is formed with a die cast cylindrical back 10, in which teeth 11 composed of steel rods are embedded. The teeth are formed in pairs from lengths of rod, bent to form three sides of a rectangle, each pair of teeth being connected by an integral cross bar 12 which, with a portion 13 of each tooth, is embedded in the cast metal back 10. I preferably indent or flatten the cross bar 12 as shown at 14, to obtain increased anchorage in the metal cast about these cross bars.

The casting 10 is also provided with an ear 16 having an aperture at 17 to receive the hook-shaped end of a tension spring 18, connected to a reinforcing flange 19 in the crotch of the divergent handle arms 20. The handle arms 20, ferrule 21 and flange 19 may all be cast integrally, and the extremities 25 of the arms 20 may be transversely flattened and a portion thereof curved to fit over the back member 10 to be connected therewith by clamping plates 26 now to be described.

The clamping plates 26 are curved at one end to embrace the under surface of the back rod 10 and are arcuately slotted, as shown at 27, to receive one of the teeth 11 which is thus made to serve as a stop. The other end of each clamping plate is formed to fit the flattened end portion of the associated handle arm 20 and is se-

cured thereto by a suitable fastening such as a bolt or rivet 28.

The arcuate portions of the clamping plates 26 and the counter-part portions of the handle arms 20 form journal boxes in which the rake head or back rod 10 may oscillate. The rake teeth which pass through the slots 21 in the clamping plates each cooperate with the associated belt 28 to hold the plate in position. Therefore a single clamping bolt for each plate 10 will be sufficient.

The clamping members 25 and 26 may be used to embrace rake back rods 10 of different diameters and lengths. Therefore, by employing removable bolts 28 and nuts 29 the same handle 15 may be interchangeably secured to rakes of different dimensions. The degree of clamping pressure exerted by the bolts 28 should be sufficient to prevent the rake head from vibrating in its bearings formed by the members 25 and 26 20 but insufficient to prevent the rake head or back bar 10 from oscillating to the extent permitted by the slots 21.

The teeth 11 are made slightly arcuate, curving toward the side occupied by the handle. Back pressure on the handle, with the teeth in contact with the ground, will cause them to fold to the extent permitted by the slots 21, and the teeth will then serve as shoes from which accumulated leaves or grass will be scraped.

By having the rake head 10, the rake teeth 11 and the handle fork arms 20 all circular in cross section, the opportunity for leaves or grass to be entangled and frictionally held is reduced to a minimum, all surfaces of these parts being 35 smooth and of minimum extent. Therefore, by also providing for an oscillation of the rake head in the forked handle journals, with a spring to hold the teeth normally in raking condition, my improved rake may be kept free from rubbish 40 with minimum effort.

My improved rake head and the metal parts of the handle will preferably be made of duralumin alloy, but the teeth will preferably be formed from sections of steel rods bent into a generally 45 U-shaped form to provide the portions 12 and 13 to be embedded in the head, and the resilient, smooth-surfaced teeth 11 projecting from the casting, as shown.

I claim:

In a self cleaning rake, the combination with a cylindrical rake head composed of light cast metal, paired steel teeth having their upper ends embedded and connected with each other within the cast metal, with the teeth projecting 55

therefrom normally in raking position, a handle having arcuate journal box members partially encircling the head, detachable journal box members complementary to the first mentioned members and each provided with a slot through which one of the rake teeth projects, the rake head being adapted to oscillate in said journal box to the extent permitted by the length of the slot, each detachable member being provided 5 with a bolt for clamping it to the associated handle connected journal box member in cooperation with the associated tooth passing through said slot to prevent swinging movement of the slotted journal member upon said bolt, the embedded ends of the teeth and their cross connections being rigidly held by the cast metal 10 against sliding movement of the teeth through the rake head under impacts of the free ends of the teeth against hard surfaces.

LAUDIE J. MRUK. 10
